HATCH CONSTRUCTION FOR RAILWAY
CAR ROOFS

James S. Swann, Homewood, Ill., assignor to
Standard Railway Equipment Manufacturing
Company, Chicago, Ill., a corporation of Dela-
ware

Application October 10, 1945, Serial No. 621,487

5 Claims. (Cl. 108—5.4)

1

The invention relates to roofs for railway cars having hatches therein for loading the cars therethrough, such as are used in refrigerator and covered hopper cars.

A roof for a railway car not only protects the lading in the car from the elements, but also prevents the superstructure of the car from weaving due to service movements of the car, and also prevents the side walls of the car from spreading or coming together due primarily to coupling the cars at abnormal speeds and application of the air brake.

To resist such weaving the railway car roof must be substantially a horizontally disposed girder including the usual stiffeners. To resist the aforesaid spreading and coming together of the side walls of the car the roof must be provided with beams extending between and supported by the side walls of the car. Such beams are usually called carlines. When the side walls of the car tend to spread, the carlines function as horizontal beams supporting a downwardly disposed load and when the side walls of the car tend to come together the carlines function as horizontal beams supporting an upwardly disposed load.

When hatch openings are cut in a car roof it is like cutting holes in a girder and the roof or girder must be reinforced accordingly.

It is the object of this invention to provide such reinforcement in a car roof having hatch openings therein and to so dispose the metallic sheets forming the car roof as to strengthen the roof around the hatch openings and furthermore to form and dispose the hatch frames and the several metallic roof sheets and associate them with the carlines (and in some cases with the purlins too) so as to reinforce the carlines in beam action by strengthening the compression and tension sides (or portions) thereof.

Another object is to associate the carlines, hatch frames and metallic roof sheets to form, in effect, a panel extending between the spaced walls of the car to resist the aforesaid weaving, as well as the aforesaid spreading and coming together of the side walls of the car.

A further object of the invention is to provide an assembly comprising a pair of carlines, preferably with purlins, extending therebetween to form hatch openings, hatch frames within said

2

openings and metallic roof sheets between said openings, which assembly can be applied to car as a unit. Such unit may also include insulating material around the hatch frame.

5 Another object is to provide means for supporting insulating material around the hatch opening above the general level of the roof to retard heat transfer into the interior of the car.

In the drawings:

10 Figure 1 shows my improved hatch structure composed of spaced carlines and spaced purlins.

Figure 2 is a section through a car having my improved hatch construction applied thereon showing the carlines, purlins, roof sheets and

15 hatch frames installed in the openings formed by the carlines and purlins. This section is drawn through the hatch frames.

Figure 3 is a section through a car having my improved hatch structure installed thereon showing the carlines, and purlins with the hatch frames and roof sheets omitted.

20 Figure 4 is a longitudinal section (on line 4—4 of Figure 2) through a car showing spaced carlines, main roof sheets and an upper roof sheet.

25 Figure 5 shows a longitudinal section (through line 5—5 of Figure 2) through a hatch frame showing the spaced carlines, main roof sheets, hatch frame and insulating blocks.

Figure 6 is a section (through line 6—6 of 30 Figure 2) through a car adjacent a side wall of the car showing the carlines, main roof sheets and an end roof sheet.

Figure 7 is similar to Figure 4 and shows the purlins extending between the carlines.

35 Figure 8 is a modified construction showing a different form of carline.

My improved hatch construction applies specifically to a car roof comprising a plurality of roof sheets extending crosswise of the car and supported upon and secured to spaced side plates 2 forming part of the side wall 3. Such roof sheets are usually secured together by some waterproof and rigidifying seam construction.

The hatch construction comprises spaced, 45 preferably apexed or arched carlines 4 adapted to extend between and be secured to the opposite side walls 3 of the car, or more specifically, secured to the side plates 2 forming parts of the side walls of the car.

I preferably also provide a pair of spaced pur-

lins 5 extending between and secured to the carlines 4 (see Figure 7) so that the spaces between the carlines 4 and each pair of purlins 5 form an opening 7 between which the hatch frames 8 are installed and secured to respective carlines and purlins. These openings 7 are usually spaced on opposite sides of the middle longitudinal line 9 of the car. Each carline 4 and also preferably each purlin 5 comprises a vertical web 12 and inwardly projecting upper horizontal flange 13 and outwardly projecting lower horizontal flange 14. The carline 4 also preferably has an inwardly projecting lower flange 15 which may be provided by the use of a T section with the upper portion thereof bent inwardly, as shown in Figure 7.

Figure 8 shows a modified carline 18 which comprises a web 19 and upper inwardly projecting flange 20 and a lower outwardly projecting flange 21. In this modification the main roof sheet 26 is provided with a flange 27 which is welded directly to the carline 18 at 28.

If the hatch frame 8 is made strong enough to form a brace between the carlines the purlins 5 may be eliminated.

The main roof sheets 24 which extend between the opposite side walls 3 of the car have one margin thereof resting upon the lower flange 14 of the adjacent carline. These main roof sheets 24 are also preferably provided with an upstanding flange 30 which is provided with a re-flange 31 which overlaps the upper flange 13 of the carline.

The upper roof sheet 32 extends between the two hatch frames 8-8 (Figure 2) (or between the purlin if used) and also extend between the carlines 4 and are secured thereto. (See Figure 4.)

Each end roof sheet 34 extends between the outer hatch frame 8 (or the outer purlin if used) to adjacent the side wall 3 of the car. (Figure 2.) Each end roof sheet 34 also extends between the carlines and is secured thereto. (Figure 6.)

Each hatch frame 8 comprises a substantially rectangular frame having an upper substantially horizontal longitudinal portion 36 adjacent each carline substantially in the plane of the upper roof sheet 32; that is, in the plane of the upper parts of the carlines.

As stated before, the carlines are beams extending between opposite walls of the car and when the side walls tend to spread apart the upper part of the beam is under compression stress and the lower part thereof is under tension stress. However, when the side walls tend to approach each other or come together, the lower part of the carline is under compression stress and the upper part thereof is under tension stress. As my improved hatch construction may be subjected to either one of these forms of stresses, I have claimed that my construction strengthens the carline in "beam action" by which I mean that the beam is strengthened so that both upper parts and lower parts thereof are better able to resist either compression stress or tensional stresses.

The upper roof sheet 32 extends between and is welded (37) directly to each hatch frame 8 (or welded to the purlins which in turn are welded to the hatch frame) (see Figure 2) and each end roof sheet 34 is welded (38) to the adjacent hatch frame 8 (or the purlin which in turn is welded to the end roof sheet) so that the upper roof sheet 32, both hatch frames 8 and both end roof sheets 34 form a continuous integral member between the opposite side walls 3

of the car to reinforce the upper part of the carlines, either in tension or compression.

The main roof sheets 24 are welded to the carlines and preferably also welded (40) directly to the upper roof sheets 32 and also welded (41) to both hatch frames 8 and also welded (42) to both end roof sheets 34 so that the main roof sheet 24, upper roof sheet 32, end roof sheets 34 and hatch frames 8 form an integral panel between the opposite side walls 3 of the car to provide a beam therebetween which could be figured independently of the carlines. However, I preferably also weld these elements to the carline so that the afore-described panel cooperates with the carlines (individually and collectively) to strengthen the carlines in "beam action," thus providing a very strong and light hatch construction.

It will be noted that the main roof sheets 24 (and 26) are in the plane of the lower parts of the carlines so as to strengthen the lower parts of the carlines either in compression or tension; i. e., in beam action.

The accompanying drawings illustrate the preferred form of the invention, though it is to be understood that the invention is not limited to the exact details of construction shown and described, as it is obvious that various modifications thereof, within the scope of the claims, will occur to persons skilled in the art.

I claim:

1. A hatch construction for a railway car having spaced walls, said construction comprising spaced carlines adapted to extend between and be secured to said walls, a hatch frame remote from each car wall which is positioned between and secured to both of the carlines, an upper roof sheet positioned in the plane of the upper parts of the carlines extending between and secured to said hatch frames and extending between and secured to said carlines, and an end roof sheet positioned in the plane of the upper parts of the carlines extending between each hatch frame and the adjacent wall and secured thereto and extending between and secured to the carlines, whereby the upper roof sheet, the end roof sheets and the hatch frames cooperate to form a continuous integral member between the walls of the car to strengthen the upper parts of the carlines in beam action.

2. A hatch construction for a railway car having spaced walls, said construction comprising spaced carlines adapted to extend between and be secured to said walls, a hatch frame remote from each car wall which is positioned between and secured to both of the carlines, an upper roof sheet positioned in the plane of the upper parts of the carlines extending between and secured to said hatch frames and extending between said carlines, an end roof sheet positioned in the plane of the upper parts of the carlines extending between each hatch frame and the adjacent wall and secured thereto and extending between the carlines, and main roof sheets positioned in the plane of the lower parts of the carlines and welded material securing said upper roof sheet, said end roof sheets, respectively, to said main roof sheets, whereby the upper roof sheet, the end roof sheets, the main roof sheets and the hatch frames cooperate to form a continuous integral member between the walls of the car.

3. A structure as defined in claim 1 wherein a main roof sheet extending between the walls of the car in a plane adjacent the lower parts of the

carline and secured thereto to strengthen the lower parts of the carlines in beam action.

4. A structure as defined in claim 1 wherein each carline is provided with an outwardly projecting flange adjacent the lower part thereof to support the margins of adjacent main roof sheets. 5

5. A structure as defined in claim 1 wherein each carline is provided with an outwardly projecting flange adjacent the lower part thereof to support the margins of adjacent main roof sheets, 10 and an inwardly projecting flange adjacent the lower part thereof to support insulating material between each carline and the hatch frame.
